UNITED STATES PATENT OFFICE.

VALENTINE F. PRETORIUS, OF CANAL DOVER, OHIO.

STREET-SWEEPING MACHINE.

No. 926,709.

Specification of Letters Patent.

Patented June 29, 1909.

Application filed March 24, 1908. Serial No. 423,005.

To all whom it may concern:

Be it known that I, VALENTINE F. PRETORIUS, a citizen of the United States, residing at Canal Dover, in the county of Tuscarawas 5 and State of Ohio, have invented certain new and useful Improvements in Street-Sweeping Machines, of which the following is a specification, reference being had to the accompanying drawings.

10 My invention relates to improvements in street sweeping machines, and it consists of the novel features of construction and the combination and arrangement of devices hereinafter fully described and claimed.

15 One object of the invention is to provide a machine of this character which may be propelled either by a motor or by horse power and which will effectively sweep up dust and dirt and convey the same to a collecting box 20 which may be conveniently emptied from time to time.

Another object of the invention is to provide a machine of this character having an improved means for mounting and adjusting 25 the sweeping brush or roll.

A further object of the invention is to improve and simplify the construction and operation of machines of this character and to provide one which will be strong and durable, convenient and easy to handle, and effective in accomplishing its intended purpose.

The above and other objects of the invention are attained in its preferred embodiment 35 illustrated in the accompanying drawings, in which—

Figure 1 is a side elevation of my improved street sweeper; Fig. 2 is a vertical longitudinal section through the same; Fig. 3 40 is a top plan view, parts being broken away and in section; Fig. 4 is a front end elevation, with parts in section, showing the brake device and the water sprinkling device; and Figs. 5, 6, 7, 8, and 9 are sectional views 45 taken, respectively, on the planes indicated by the lines 5—5, 6—6, 7—7, 8—8, and 9—9 in Fig. 1.

My improved street sweeper comprises a substantially rectangular body or frame 1 50 having side beams 2 connected by suitable cross bars or beams. The body is supported at its front by steering wheels 3 and at its rear by driving wheels 4. The front wheels are journaled upon the front axle 5 which is 55 connected to the body by a king bolt 6 and a

fifth wheel or turn table 7, the last mentioned parts being constructed and arranged as more clearly shown in Fig. 4. To permit the machine to be operated by horse power a suitable socket 8 is carried by the front axle 60 for the reception of a draft tongue or pole. The rear wheels 4 are journaled upon a rear axle 9 rigidly connected by truss bars 10 to the rear portion of the frame 1.

When the machine is to be driven by a 65 gasoline engine or any other form of motor 11, the latter is mounted upon the rear portion of the body 1 and is connected by gearing to the rear wheels 4 which have upon their peripheries or rims transverse ribs 12 70 to prevent them from slipping. The shaft of the motor 11 has upon one end a fly wheel and upon its other end a transmission gear 13 of any suitable form and construction. As illustrated, said transmission gear is 75 provided with a sprocket 14 and with two operating levers 15, 16. The lever 15 is adapted to throw said gear into and out of operation and is connected by a rod 17 to a hand lever 18. The other lever 16 is adapted to control the reverse portion of the transmission gear 13 and is connected by a rod 19 to a hand lever 20. Said hand levers are arranged within convenient reach of the operator and provided with the usual hand controlled pawl and ratchet locking devices. The sprocket 14 is connected by a sprocket chain 21 to a sprocket wheel 22 fixed to a transverse shaft 23 suitably journaled upon the frame or body of the machine. Connected to the shaft 23 are two gears 25 which mesh with gears 26 suitably journaled upon the frame or body and adapted to mesh with cog wheels or gears 27 arranged upon the inner faces of the rear drive wheels 4. Each 95 of said gears 27 has a toothed rim connected by spokes 27^a to a hub 27^b which is bolted to the hub of the wheel 4. Said toothed rim of the gear 27 is provided upon one side with a projecting flange 28 which latter has projecting ears 29 which are bolted to the rim of the wheel 4. The spokes of the gear and the ears 29 may be reinforced by strengthening webs, as illustrated.

My improved sweeping apparatus which is 105 mounted on the body 1 comprises a rotary sweeping brush or roll 30, an inclined chute 31 and an endless elevator 32 which conveys dirt and dust swept by the brush upon the lower part of the chute up the latter and 110

into a collecting box or receptacle 33. The brush 30 is disposed transversely adjacent to the rear wheels and may be of any suitable form and construction, but I preferably make it of a cylindrical core of wood composed of two half-sections 34 having steel bristles radiating from them. The core sections 34 are formed with opposing centrally disposed longitudinal grooves to receive a squared shaft 35 and are retained upon the latter by several removable sectional clamping bands 36, as clearly shown in the drawings. By constructing and mounting the brush in this manner it will be seen that it may be readily removed from its shaft and replaced by a new one without removing the shaft from its bearings or hangers.

The brush shaft 35 carries, adjacent its ends, gears or pinions 37 which mesh with the cog gears 27 on the rear wheels 4, thereby causing the brush to be revolved in the reversed direction to that of the rotation of said wheels. A pawl and ratchet connection is provided between the gears 37 and the shaft 35. Each of these pawl and ratchet devices consists of a plurality of spring pressed pawls 38 pivoted to one of said gears and adapted to mesh with ratchet notches 39 formed in the shaft 35, as clearly shown in the drawings.

The brush shaft 35 is mounted so that it may be adjusted toward and from the ground or street to compensate for wear. This mounting is effected by providing on the opposite sides of the body two rear hanger bars or links 40 having their upper ends pivoted at 41 and their lower ends formed with bearings to receive the reduced ends of the shaft 35. I also provide a pair of front hanger and adjusting bars or links 42 also formed at their lower ends with bearings to receive the reduced ends of the shaft 35. The upper ends of the forward bars 42 are connected by a cross rod 43 which may be placed in any one of a longitudinal series of keeper seats 44 formed in a plate 45 on both of the side bars of the body 1. Said cross bar 43 is adapted to be secured in its adjusted position by locking plates 46 also formed with notches and pivoted at one of their ends at 47. The other end of each plate 46 is adapted to be secured by a bolt or other removable fastening 48. It will be seen that as the bristles 30 wear away the rod 43 is adjusted rearwardly to lower the brush and cause it to properly contact the street.

For the purpose of throwing the brush out of gear I provide means for elevating and supporting the rod 43 after its locking plate 46 has been unfastened. This means comprises two chains 49 connected to the rod at their lower ends and having their upper ends connected to and wound upon a cross shaft 50 journaled in suitable bearings on brackets 51 and having at one end a hand wheel 52

and a ratchet wheel 53, the latter being adapted to be engaged by a locking pawl 54.

The chute 31 is inclined upwardly and forwardly and is constructed of sheet metal and has upright side flanges 55. Its intermediate portion is preferably strengthened by cross bars and its upper end is pivotally hung by bending it, as shown at 56, around a transverse hanger rod 57 arranged upon the body 1 at the rear edge of the dust box 33. The lower rear end of the chute is curved to fit up close to the brush and the side flanges of said end of the chute are shaped to receive the ends of the brush between them. This lower rear end of the chute is supported from the ground or street by caster wheels 58 journaled in bearings on a cross bar 59 secured to the bottom of the chute. For the purpose of raising the lower ends of the chute off of the ground I provide upon its opposite sides 85 chains 60 having their upper ends connected to and wound upon a transverse shaft 61 provided with a crank handle 62 and a pawl and ratchet locking device 63.

The dirt and dust brushed upon the curved lower end of the chute by the brush 30 is carried upwardly through the chute by the lower stretch of the endless carrier or elevator 32, which latter consists of sprocket chains connected by angle metal cross bars 64. The latter have one 95 of their flanges projecting at right angles from the sprocket chains and are adapted to engage the dirt upon the chute and move it upwardly through the same. The lower portions of the sprocket chains pass over 100 sprocket wheels 65 arranged on a transverse shaft in suitable bearings at the lower end of the chute and also over sprocket wheels upon a transverse shaft 66 journaled in suitable bearings upon the side beams of the body 1 105 and connected by meshing gears 67 to a similar transverse shaft 68. The latter has upon one of its ends a sprocket wheel which is connected by a sprocket chain 69 to a driving sprocket wheel 70 bolted to the hub of one of the rear wheels 4. It will thus be seen that the endless elevator will be driven from the rear wheels.

The dust collecting box 33 has a bottom composed of two doors 71 hinged at 72 to 115 drop downwardly. Said doors are raised and supported in their closed position by chains 73 having their upper ends fixed to and wound upon a transverse shaft 74 which is provided with a hand wheel 75 and a pawl 120 and ratchet locking device 76. The top of the box 33 is closed by an elevated hood or casing 77 in the rear side of which is an opening closed by a screen 78 and in the front side of which is an opening 79. The latter may 125 be opened by the operator when he desires to inspect the mechanism within the casing or hood.

Arranged above and in rear of the brush 30 is a rotary fan 80 mounted on a transverse 130

shaft 81 journaled in hangers 82 depending from the side bars of the body 1 and strengthened by inclined braces, as shown. The fan is provided at its rear with a casing or hood 83 and it is driven from one of the gear rings 27 by providing a pinion 84 which meshes with said ring. This pinion is fixed upon a transverse shaft 85 in the hangers 82 and is connected by a sprocket chain gearing 86 to the fan shaft 81. The fan 80 is arranged above and slightly in rear of the brush and in advance of the depending portion of the casing or hood 83 so that it will blow the dust forwardly and upwardly upon the chute 31 and into the dust box 33.

For the purpose of steering the wheel I provide an upright steering bar 87 having at its upper end a hand wheel and at its lower end chains 88 which connect it to the front axle. Mounted upon the front of the body 1 is a sprinkling device comprising a transversely disposed water tank 89 provided with an outlet pipe 90 which leads to a transverse sprinkler head 91. The valve 92 in the pipe 90 is controlled by a rod 93 which has its upper end suitably connected to a lever 94 pivoted intermediate its ends, as shown. The lower end of the lever is connected by a link 95 to a treadle 96 arranged within reach 50 of the operator who sits on a seat 97 on top of the hood or casing 77. A spring 98 is adapted to actuate the lever 94 to close the valves 92.

The top of the machine is preferably provided with a cover 99.

In Fig. 4 of the drawings I have shown a brake device comprising two transversely disposed brake levers 101 pivoted intermediate their ends in brackets 102 and having at 40 their outer ends shoes 103 to engage the front wheels. The inner ends of the brake levers are united by a chain 104 and they are actuated downwardly to elevate the brake shoes by coil springs 105. The chain 104 passes 45 over a guide pulley 106 and is attached to and wound upon a transverse shaft 107 connected by bevel gears 108 to an upright operating shaft 109 having a hand wheel at its upper end. This shaft 109 has a pawl and 50 ratchet locking device 110.

In operation, it will be seen that when my improved street sweeper is driven by a motor the operator or driver can control all of its various parts while sitting upon the seat 97. Power from the engine is used to drive the 55 rear wheels 4 to propel the machine and from these rear wheels power is taken to drive the brush, the elevator, and the fan. When the dust box becomes filled it may be readily 60 damped by dropping its doors or bottom sections and by turning the machine sharply it may be moved away from the deposited

pile of dirt without the latter interfering with the pan.

While I have shown and described in detail 65 the preferred embodiment of my invention it will be understood that I do not wish to be limited to the precise construction set forth and that various changes in the form, proportion and minor details may be resorted 70 to without departing from the spirit or sacrificing any of the advantages of the invention.

Having thus described my invention what 75 I claim is:

1. In a street sweeper, the combination of a body having supporting wheels, an inclined chute, a dust box at the upper end of the latter, a rotary brush at the lower end of the chute, a casing or hood in rear of and above 80 the brush, and a rotary fan arranged in said casing or hood in rear of and above the brush for directing the dust from the latter up the chute and into the dust box.

2. In a street sweeper, the combination of 85 a body having supporting wheels, an inclined chute, a dust box at the upper end of the latter, a rotary brush at the lower end of said chute, a rotary fan arranged above and in rear of the brush, a motor upon the body, 90 means for driving the wheels of the body from said motor, and means for driving the brush, elevator and fan from said wheels.

3. In a street sweeping machine, the combination of a body, wheels for the latter, a 95 rotary brush, a shaft for the latter, an adjusting plate having notches or seats, brush adjusting links and a cross bar connecting the last mentioned links and adapted to engage the seats or notches in said adjusting 100 plate.

4. In a street sweeping machine, the combination of a wheeled body, a rotary brush, a shaft for the latter, pivoted hanger links for the shaft, adjusting links, a cross bar connecting said adjusting links, means for adjusting the cross bar forwardly and rearwardly and means for raising and lowering the cross bar.

5. In a street sweeping machine, the combination of a wheeled body, a rotary brush, a shaft for the latter, pivoted hanger links for the shaft, adjusting links, a cross bar connecting said adjusting links, means for adjusting the cross bar forwardly and rearwardly, a winding shaft and a chain connecting the cross bar to said winding shaft.

In testimony whereof I hereunto affix my signature in the presence of two witnesses.

VALENTINE F. PRETORIUS.

Witnesses:

VIC. WENTZ,
JAS. A. BARR.
